UNITED STATES PATENT OFFICE

143,373

DESIGN FOR A PICTURE FRAME SPACER

George Wade Vreeland, St. Paul, Minn.

Application June 27, 1945, Serial No. 120,371

Term of patent 3½ years

(Cl. D54—9)

To all whom it may concern:

Be it known that I, George Wade Vreeland, a citizen of the United States, residing at St. Paul, county of Ramsey, and State of Minnesota, have invented a new, original, and ornamental Design for a Picture Frame Spacer, of which the following is a specification, reference being had to the accompanying drawing, forming part thereof.

Figure 1 is an elevation view of my picture frame spacer, showing my new design;

Figure 2 is a side elevational view of the same; and

Figure 3 is an end elevational view of the same.

I claim:

The ornamental design for a picture frame spacer, as shown.

GEORGE WADE VREELAND.
